CLOTHES TREE

William Sihler, Decorah, Iowa

Application May 17, 1935, Serial No. 22,061

1 Claim. (Cl. 211—178)

This invention aims to provide an inverted U-shaped garment support, of adjustable width, the uprights of which may be brought together to form a single post, thereby converting the device 5 into a tree at the will of an operator, novel means being provided for housing certain of the garment hooks, and the connections between the uprights, when the device is changed into a tree. Other objects may be attributed, without specific 10 enumeration, to the parts hereinafter described. The form shown and described is satisfactory, but a mechanic may alter it, without departing from the spirit of the invention, if he keeps within the scope of what is claimed.

Fig. 1 shows in side elevation, a garment support constructed in accordance with the invention, the support being extended, and parts being in section;

Fig. 2 is an elevation showing the device converted into a tree;

Fig. 3 is a top plan, the support being extended;

Fig. 4 is a top plan, the support being converted into a tree;

Fig. 5 is a vertical section showing the parts 25 as they will appear when the device is converted into tree form;

Fig. 6 is a cross section on the line 6—6 of Fig. 5;

Fig. 7 is a composite view, in perspective, disclosing one of the supporting elements and the socket that receives it detachably.

Fig. 8 is a perspective view showing details of the connection that joins the posts.

The garment support that characterizes this 35 application comprises standards 1. Each standard 1 includes a base 2 and an upright 3 fixed to the base at the inner edge of the base. The base 2 is carried on castors 50. On its inner side, one post 3 has projections 4. The projections 4 are 40 adapted to be received in seats 5 in the other post, when the posts are brought together to form a tree, as in Figs. 2 and 5. The projections 4 and the seats 5 serve to keep the posts 3 in alignment, when the posts are brought together.

On the inner side of each post 3, near to the upper end thereof, there is a longitudinal recess 6. Notches 8 are formed in the posts 3, near to the lower ends of the recesses 6. Tapered sockets 9 are secured to the forward sides of the 50 posts 3. The sockets 9 are shaped to receive the tapered feet 10 of removable upstanding suspension elements 11, adapted to receive a coat or hat.

The posts 3 are joined, near to their upper ends, 55 by a connection 12. The connection 12 em-

bodies two bar-like members 14. The outer ends of the bars 14 are pivoted at 15 to the posts 3, within the recesses 6. Oppositely-extending brackets 16 are secured to the inner end portion of each bar 14. The bracket 16 of one bar 14 engages the upper edge of the other bar. Therefore, the bar 14 cannot knuckle down on the pivot elements 15, in the direction of the arrow A in Fig. 1. The bracket 16 of each bar 14 has a depending flange 17 overlapping the outer surface of the other bar 14 and preventing the bars from separating horizontally. The brackets 16 afford a means whereby the connection 12 is made longitudinally extensible, at the will of an operator, so that the operator can have a wide 15 garment support, or a narrow one, as his taste dictates, the construction of the device being such that it can be used to advantage in a spacious house, or in a small one.

There are vertical elongated slots 18 in the 20 bars 14. Fulcrum members 19, such as pins, are mounted in the bars 14 and extend across the slots 18. Garment hangers 20 are located in the slots 18 and are mounted intermediate their ends to swing on the fulcrum members 19. Each garment carrier 20 is provided at its upper end with a hat peg 21, and at its lower end with a hook 22 or the like. Coat hangers (not shown) may be suspended from the hooks 22.

The function of the various hat and garment 30 carriers will be obvious at a glance, and may be dismissed with the statement that if the operator does not wish to have the suspension elements 11 of Fig. 7, he can remove them.

As to the extensible and contractible features 35 of the device, the operator may push the posts 3 toward each other, or pull them apart, varying the length of the connection 12 and the number of garment carriers 20 that are in working position. When the posts 3 are moved toward each 40 other, the brackets 16 engage the hat pegs 21 and swing the garment carriers 20, one at a time, into housed position, within the slots 18.

If the tree form of Fig. 2 is preferred, the inner ends of the bars 14 of the connection 12 45 first are swung upwardly, to free the bracket 16 of one bar from the other bar. Each bar 14 then is swung down on the pivot element 15, until the bar is housed in the recess 6 of the corresponding post 3, the garment hangers 20 swing- 50 ing automatically into vertical position in the slots 18 of the bar, although the garment hanger can be moved into that position by hand, should there be some friction between the garment hanger and the bars. After the bars 14 are housed 55

- in the recesses 6, the posts 3 may be moved into contact, as in Figs. 2 and 5, the projections 4 of one post entering the seats 5 of the other post, and a stable, compact clothes tree being provided,
- 5 the suspension elements on the clothes tree being the parts 11, as Fig. 2 will disclose. The purpose of the notches 8 in the posts 3 of Fig. 1 is to receive the brackets 16, when the article is arranged in the tree form of Fig. 2.
- 10 One of the chief virtues of the device is that it is readily adaptable to the size of the room in which it is used, and finds favor equally with the owners of small or large houses.
- 15 What is claimed is:
- 15 A garment support comprising standards, a connection including bars pivoted at their outer ends to the standards, whereby the bars may be folded downwardly to permit the standards to be brought together to form a clothes tree, the bars

being provided with elongated slots, means extended across the upper edges of the bars, and leaving the slots open at the bottom, for joining the inner ends of the bars together releasably, and for relative sliding movement to permit the standards to be disposed at different distances from each other, and garment hangers located in the slots and extended below the bars, the hangers being pivoted intermediate their ends to the bars, the hangers extending upwardly 10 above the bars, to form upstanding hat pegs, the hangers being of such width that they will be housed in the slots, in parallel relation to the bars, when the bars are folded as aforesaid, said means engaging the upstanding hat pegs, to swing 15 the hangers and the hat pegs into the slots when the standards are moved toward each other.

WILLIAM SIHLER.
